No. 764,123.

PATENTED JULY 5, 1904.

J. J. HANUS & W. A. TUCKER.

INSECT EXTERMINATOR.

APPLICATION FILED JULY 10, 1903.

NO MODEL,

UNITED STATES PATENT OFFICE.

JOSEPH JOHN HANUS AND WILLIAM ANDREWTON TUCKER, OF TAYLOR,
TEXAS.

INSECT-EXTERMINATOR.

SPECIFICATION forming part of Letters Patent No. 764,123, dated July 5, 1904.

Application filed July 10, 1903. Serial No. 164,969. (No model.)

To all whom it may concern:

Be it known that we, JOSEPH JOHN HANUS and WILLIAM ANDREWTON TUCKER, citizens of the United States, residing at Taylor, in the county of Williamson and State of Texas, have invented a new and useful Insect-Exterminator, of which the following is a specification.

This invention relates to insect-exterminators of that class which are intended and adapted especially for the purpose of destroying the pests which are known as "cotton-weevils;" and it has for its object to provide a device of this class which may be constructed and operated at a moderate expense and which shall possess superior advantages in point of simplicity, durability, and general efficiency.

With these ends in view our invention consists in the improved construction, arrangement, and combination of parts, which will be hereinafter fully described, and particularly pointed out in the claims.

In the accompanying drawings we have illustrated a simple and preferred form of embodiment of our invention; but we desire it to be understood that we do not limit ourselves strictly to the structural details therein set forth, but reserve the right to such changes and modifications as may be resorted to within the scope of our invention and without departing from the spirit or sacrificing the efficiency of the same.

In said drawings, Figure 1 is a side elevation, partly in section, of a device constructed in accordance with the principles of our invention. Fig. 2 is a top plan view of the same. Fig. 3 is a transverse sectional view, on a larger scale, of the heating box or chamber. Fig. 4 is a detail view of the suction-head used in connection with the machine. Fig. 5 is a sectional detail view taken on the line 5-5 in Fig. 3.

Corresponding parts in the several figures are indicated by similar numerals of reference.

The frame 1 of our improved device is supported upon an axle 2, having transporting-wheels 3, 4. The dimensions are such that two rows of plants will be included between the wheels, the device operating between the

rows, as will be readily understood. One of 50 the wheels, 4, is a traction-wheel, and the spokes thereof, 5, 5, are extended radially beyond the periphery of the rim 6, thus forming ground-engaging fingers 7, by means of which the said wheel will be positively revolved. The said drive-wheel 4 is provided on its inner side with a sprocket-wheel 8, from which motion may be transmitted to the operative parts of the device. Shafts 9, having the usual means for the attachment of the 60 draft, are supported upon the axle and may be said to constitute a part of the frame.

The frame of the machine suitably supports a fan-casing 10, having bearings for a shaft 11, carrying a fan 12. The fan-shaft projects 65 beyond one side of the casing and carries a sprocket-wheel 13, which is connected by a chain 14 with the sprocket-wheel 8 upon the traction-wheel 4, from which motion at the desired rate of speed may thus be transmitted 70 to the fan. The fan-casing 10 is provided near its lower end with a rearwardly-facing suction-tube 15 and near its upper end with a rearwardly-extending blast-tube 16.

The suction-tube 14 is connected, by means 75 of a flexible joint 17, which may be constructed of canvas, leather, rubber, or other suitable material, with a suction-head 18, which is of flattened funnel shape, the mouth 19 of said suction-head being long and narrow, as will 80 be readily seen in the drawings. In order to prevent the entrance into said suction-head of material that will be liable to choke the machine, the mouth thereof is provided with a plurality of appropriately-spaced bars 20. 85 This suction-head may be constructed of metal—such as tin or sheet-iron—and it is provided with two laterally-extending branches 21 on opposite sides thereof, said branches being curved in an upward and outward direction and provided with flaring or V-shaped mouths 22, which, like the mouth 19 of the main suction-head, are provided with grate-bars 23 to prevent the entrance of material that would be liable to obstruct the operation 90 of the device.

24 designates a box or chamber the top 25, front end 26, and portion 27 of the bot-

tom of which is preferably constructed of sheet metal, the remainder of said box, which is approximately rectangular in shape, (although it may within the scope of our invention be of any desired shape,) being constructed of wire-netting or foraminous material which will admit of the circulation of air. That portion 28 of the bottom which lies behind the solid portion 27 is connected flexibly 5 with said bottom portion 27, as by means of spring-hinges 29, so that said portion 28, which is transversely curved, may vibrate during the progress of the machine. Said vibrating bottom portion 28 may also within the 10 scope of our invention be positively vibrated, if so desired. Owing to the transverse curvature of the bottom portion 28, the latter will be open at its rear end for the gradual escape of material accumulated thereon.

15 20 Suitably attached to the under side of the top 25 and depending from the same is a deflecting or what we term a "target" plate 30, the lower edge of which is disposed a short distance above the rear edge of the solid bottom portion 27. This target-plate is provided with a plurality of perforations 30^a in order to prevent it from presenting too much resistance to the blast to which it will be exposed, as will be presently described. Suitably supported upon the frame of the machine below said solid portion is a heating apparatus which may consist of a gasolene-torch 31, of ordinary construction, although we do not limit ourselves to a heating apparatus of this character.

25 30 The blast-tube 16 of the blower is suitably connected with the solid front side of the box 24 directly in front of the target 30. Suitably attached to the tongue or to some other 35 supporting part of the frame of the machine are a couple of rearwardly-extending and diverging stalk-engaging members, which will be seen at 32 and which when the machine progresses will engage the stalks of the growing plants, causing the latter as they pass out of engagement with the members or "shakers" 40 45 50 55 60 65 70 75 80 85 90 95 100 9885 9890 9895 9900 9905 9910 9915 9920 9925 9930 9935 9940 9945 9950 9955 9960 9965 9970 9975 9980 9985 9990 9995 9999

will be drawn through the fan-casing and expelled through the blast-pipe and into the box 24, whereby they are forcibly thrown against the deflector or target 30 and caused to drop upon the solid bottom section 27, which is intensely heated by the heating apparatus placed underneath, and thereby destroying the insects and scorching the infected bolls. The residue is permitted to dump onto the vibrating bottom section 28, at the rear end of which it is eventually discharged. The branches 21 of the suction-head, which, as described, are curved outwardly and upwardly, will greatly assist in the successful and complete operation of the device by engaging the under sides of the limbs and leaves of the plants, removing from the same any adhering insects and infected bolls, which are all carried through the suction-tube and fan-casing to the box 24, where they are destroyed. It is obvious that, owing to the flexible connection 17 between the suction-tube 15 and the suction-head, the latter may be supported when desired at any elevation above the ground, supporting means in the shape of a chain 35 and hook 36 being provided for the purpose.

Having thus described our invention, we claim—

1. In a device of the class described, a suction-head having laterally-extending upwardly and outwardly curved branches.
2. In a device of the class described, a flattened, funnel-shaped suction-head provided with laterally-extending upwardly and outwardly curved branches.
3. In a device of the class described, a flattened funnel-shaped suction-head provided with laterally-extending upwardly and outwardly curved branches, the mouths of said head and branches being provided with transversely-disposed grate-bars.
4. In a device of the class described, a heating-chamber having a deflecting-plate extending downwardly from the top thereof, a heater disposed below the front end of said casing, a blower having a suction-tube and a blast-pipe, the latter connected with the front end of the heating-chamber in front of the deflector.
5. In a device of the class described, the combination with a blower, a suction-pipe, a blast-pipe connected with said blower and a suitably-supported heating apparatus, of a heating-box disposed within the latter and connected with the blast-tube of the blower, said heating-chamber having a solid bottom portion at the front end thereof, and a deflector depending from the top and terminating at a distance above the rear edge of the solid bottom portion.
6. In a device of the class described, a heating-chamber having a vibratory bottom section.

7. In a device of the class described, a heating-chamber having a vibratory, transversely-curved bottom section.
8. In a device of the class described, a heating-chamber having a solid bottom portion, heating apparatus disposed underneath the same, and a vibratory bottom section hingedly connected with said solid bottom portion.
9. In a device of the class described, a heating-chamber having a solid bottom portion, a heating device disposed below said solid bottom portion, a vibratory bottom section hingedly connected to the rear edge of said solid bottom portion, a deflector within the chamber, and means for forcibly discharging into said chamber and against said deflector, material to be destroyed.
10. In a device of the class described, a heating-chamber having a solid metallic top, a front, a solid bottom portion, sides and rear end of foraminous material, and a transversely-curved vibratory bottom plate hingedly con-
- nected with the rear edge of the solid bottom portion, in combination with a heater disposed beneath the latter, and means for discharging into said chamber, material to be destroyed. 25
11. In a device of the class described, a heating-chamber, means for discharging thereinto material to be destroyed, a deflector within 30 said heating-chamber, heating apparatus disposed beneath said heating-chamber, and means for automatically discharging the contents of the latter after being subjected to destructive heating. 35

In testimony that we claim the foregoing as our own we have hereto affixed our signatures in the presence of two witnesses.

JOSEPH JOHN HANUS.
